UNITED STATES PATENT OFFICE.

LEHMAN LEVY, OF CHICAGO, ILLINOIS, ASSIGNOR TO SCHWARZSCHILD & SULZBERGER CO.,
OF NEW YORK, N. Y., A CORPORATION OF NEW YORK.

REFRIGERATING APPARATUS.

No. 889,627.

Specification of Letters Patent.

Patented June 2, 1908.

Application filed April 2, 1906. Serial No. 309,450.

To all whom it may concern:

Be it known that I, LEHMAN LEVY, a citizen of the United States, residing at Chicago, in the county of Cook and State of Illinois, have invented certain new and useful Improvements in Refrigerating Apparatus, of which the following is a specification.

My invention pertains to means for cooling the air in a refrigerator, and more especially in a refrigerator of large size such as is used in meat packing establishments. To chill the air which circulates through the chamber or chambers containing the products to be preserved I employ a number of 10 perforated pipes from the holes in which escapes cold brine, and in order that the latter may have a large surface to spread over so as to effectually reduce the temperature of the air I hang on each pipe a curtain or sheet, 20 desirably of woven fabric, which becomes wet or saturated by the brine. To render the distribution of the salty liquid over the curtain substantially uniform the latter is provided at its top edge with a hem within 25 which one of the apertured discharge pipes fits so as to support the curtain, and by making the hem of such depth that the pipe loosely fits therein a sort of pocket or bag is formed in the hem below the pipe. The 30 turned-over strip of the hem is attached at intervals to the main body of the curtain by means of rivets or other fastening devices, but I preferably use interrupted stitching to secure the two parts together. To prevent 35 the brine from spouting out of the ends of the hem simple metallic clamps close the ends of the hem about the pipe thereby causing the brine which escapes from the apertures of the discharge pipe to trickle through the 40 stitches of the hem and through the spaces formed by the unstitched portions, whereupon the liquid evenly distributes itself over the suspended sheet cooling the air currents with which it comes in contact.

In order to intercept the air currents and prevent them from passing by the curtains without a sufficient reduction in temperature I use a number of banks of pipes and curtains or sheets each of which has a plurality of parallel pipes and curtains which extend obliquely to the air currents so that the latter are brought more directly into contact with the brine-laden curtains thereby compelling the extraction of the heat from 55 the air.

The preferred embodiment of my invention is illustrated in the accompanying drawings wherein:

Figure 1 is a perspective view of the brine distributing mechanism; Fig. 2 is a view showing a supply or feed pipe, a perforated discharge pipe and a distributing curtain hung thereon; Fig. 3 is a section of the device illustrated in Fig. 2 on the line 3-3 as viewed in the direction of the arrows; Fig. 4 is a vertical cross-section of the discharge pipe and a portion of the curtain on the line 4-4 of Fig. 2; Fig. 5 is a vertical section of a simple form of refrigerator equipped with my improved cooling means; and Fig. 6 is a horizontal section of the refrigerator on line 6-6 of Fig. 5.

Referring to Fig. 1 of the drawing the brine or other cooling medium is brought to the distributing curtains through a main feed pipe 10 which connects with the upright pipe 11, the latter connecting with the transverse branch feed pipe 12 supplied with valves 13 on either side of pipe 11. Pipe 12 is connected to a number of smaller feed pipes 14, 20 supplied with valves 14^a at the opposite ends of which are laterally extended supply or feed pipes 15, each equipped at its opposite ends with plugs or caps 16. Along the upper surface of such feed pipe 15 is a series of 35 threaded holes 17 in each of which is inserted an elbow 18 having an integral nipple 19 fitting in and engaging the threads of the aperture 17. These elbows extend somewhat obliquely from the pipe 15 as do also the discharge pipes 20 which are fitted thereto, each of the pipes 20 having at its outer end a cap 21 and along its lower surface a number of 40 apertures 22 communicating with the interior.

In Figs. 5 and 6 there is illustrated one of the simplest forms of refrigerators cooled by parallel curtains wet with a cooling medium such as brine, the curtains cooling the warm air as it rises from the cooling chamber, the 100 air then descending into the cooling compartment to again abstract heat from the food or other supplies therein. The refrigerator 29, the walls of which are packed with any suitable material 30, is divided into two compartments 31 and 32 the former of which contains the wet curtains while the latter is adapted to receive the material or food to be cooled. Compartment 32 has the usual door 105 33 and communicates with the upper portion 110

of chamber 31 by the passage 34. On the other side or end of the refrigerator the cool air from chamber 31 is allowed to descend into food compartment 32 through the 5 passage 35. A brine supply pipe 36 extends through one wall of the refrigerator into its interior where it is connected with a feed or distributing pipe 37 which conveys the brine to a plurality of parallel perforated discharge 10 pipes 38 each of which is equipped with a curtain or fabric sheet 39. The construction of these pipes and curtains is substantially like that shown in the other figures of the drawing so that a detailed description there- 15 of appears to be unnecessary. The warm air from the food or storage chamber of the refrigerator passes through the tube or passage 34 to compartment 31 where it is cooled and afterwards descends through the passage 20 35 to the supply compartment again. It should be noted that the curtains 39, although parallel, are all disposed at an angle to the normal direction of an air current entering through passage 34 to chamber 31 and 25 leaving the latter by passage 35. Owing to this construction the air is compelled to travel or graze along the curtains so that it is effectively cooled. If the curtains were substantially in line with the passage or con- 30 duct for the air through chamber 31 the air would pass between the curtains without striking against them to any great extent whereby the reproduction in temperature of the air would not be so effectively secured. 35 On each discharge pipe 20 is hung a curtain 23, preferably made of fabric, and at its upper end each curtain has a hem 24 the turned-over part of which, 25, is attached to the main body of the curtain by interrupted 40 stitching 26. Each hem 24 is of such a size that when placed over its discharge pipe there is formed below the latter a sort of pocket or compartment 27 into which the brine is adapted to flow through the apertures 22. The ends of each hem are closed about the pipe by metallic clips 28 which are placed over the pipe and then squeezed together along the end of the hem so as to bring the two edges of the hem together 45 thereby preventing the escape of brine from the ends of the hem.

The operation of the device described is as follows:—The brine or other cooling liquid passes through pipes 10, 11, 12 and 14 to the 50 series of feed pipes 15 which convey the brine to the obliquely extended perforated discharge pipes 20. The liquid then passes through the apertures 22 into the pockets formed in the hems and then trickles through 55 the stitching 26 and through the spaces provided by the interrupted stitching to the main bodies of the curtains down which it flows and over which it evenly distributes itself. By striking these curtains or sheets the currents of air are reduced considerably

in temperature and are then conveyed to the compartment or chambers containing the perishable products. By disposing these curtains obliquely to the air currents they are caused to strike the same and prevent a 70 direct passage of air between the curtains without a sufficient reduction of temperature.

It will be obvious to those skilled in the art that various changes may be made in the structure described herein without departing from the substance or essence of my invention as set forth in the following claims.

I claim:

1. In a device of the character described, 80 the combination of a compartment having an admission and a discharge passage, and a plurality of substantially-parallel curtains within said compartment and disposed obliquely to a direct line between said admission and discharge passages, said curtains being adapted to be wet with a cooling medium whereby to cool the air and create an air current through said compartments and passages, substantially as described. 90

2. In a device of the character described, 95 the combination of a feed pipe, and substantially-parallel perforated discharge pipes connected with said feed pipe and projecting therefrom at an oblique angle, whereby a cooling medium fed to said discharge pipes by said feed pipe is delivered through the perforations, substantially as described.

3. In a device of the character described, 100 the combination of a feed pipe, substantially-parallel perforated discharge pipes connected with said feed pipe and projecting therefrom at an oblique angle, and a distributing curtain hung on each of said discharge pipes, whereby a cooling medium fed to said discharge pipes by said feed pipe is delivered through the perforations to the distributing curtains, substantially as described. 105

4. In a device of the character described, 110 the combination of a feed pipe, substantially-parallel perforated discharge pipes connected with said feed pipe and projecting therefrom at an oblique angle, and a distributing curtain associated with each of said discharge pipes, whereby a cooling medium fed to said 115 discharge pipes by said feed pipe is delivered through the perforations of said discharge pipes to the distributing curtains, substantially as described.

5. In a device of the character described, 120 the combination of a feed pipe, substantially-parallel discharge pipes connected with said feed pipe and projecting therefrom at an oblique angle, said discharge pipes having perforations on their under sides, and a distributing curtain for each of said discharge 125 pipes, each curtain having a hem within which its discharge pipe fits, whereby a cooling medium fed to said discharge pipes through said feed pipe is delivered to the 130

curtains through the perforations of the discharge pipes, substantially as described.

6. In a device of the character described, the combination of a perforated discharge pipe and a curtain having a hem, the turned-over part of said hem being secured to the main body of the curtain by interrupted stitching, said pipe fitting in said hem, substantially as described.

10 7. In a device of the character described, the combination of a perforated discharge pipe and a curtain having a hem, the turned-over part of said hem being fastened at intervals to the main body of the curtain, and said pipe fitting in said hem, substantially as described.

8. In a device of the character described, the combination of a perforated discharge pipe, a curtain having a hem, said pipe fitting 20 in said hem, and means to close the ends of said hem, substantially as described.

9. In a device of the character described, the combination of a discharge pipe perforated on its under side, and a curtain having 25 a hem, said pipe loosely fitting in said hem and supporting said curtain, whereby a pocket or compartment is provided in said hem below said pipe allowing distribution

of the cooling medium on the curtain lengthwise the pipe, substantially as described.

10. In a device of the character described, the combination of a perforated discharge pipe, a curtain having a hem, the turned-over part of said hem being attached to the main body of the curtain by interrupted stitching, said pipe loosely fitting in said hem, and supporting said curtain, and means to close the ends of said hem whereby a pocket is formed in the lower part of said hem, substantially as described.

11. Brine distributing apparatus comprising in combination a main, discharge pipes having discharge openings, and connected with said main, and extending laterally therefrom, said discharge pipes being capable 45 of being swung at their free ends to vary the angle of their inclination to the main, valves interposed in said discharge pipes, and curtains of textile fabric hung over and supported by said discharge pipes, substantially 50 as described.

LEHMAN LEVY.
